(57) CLAIM

The ornamental design for the furniture ornamentation, as shown and described.

DESCRIPTION

FIG. 1 is a perspective view of a furniture ornamentation in accordance with the present invention;

FIG. 2 is a front view of the furniture ornamentation, the back view being a mirror image thereof;

FIG. 3 is an enlarged view of the portion of the furniture ornamentation indicated by the circle in FIG. 2;

FIG. 4 is a top view of the furniture ornamentation, the left side view being a mirror image thereof; and,

FIG. 5 is a right side view of the furniture ornamentation, the left side view being a mirror image thereof.

The various pieces of furniture, as shown in broken lines in the drawings, are included to disclose the environment related to the claimed design for form no part of the present invention.
